UNITED STATES PATENT OFFICE

2,475,120

TUBULAR AIR HEATER

Thomas Young, Spokane, Wash.

Application July 25, 1944, Serial No. 546,487

1 Claim. (Cl. 126—72)

1

This invention relates to stoves and more particularly to a stove intended for heating a room or building, it being one object of the invention to provide a stove or heater formed with a combustion chamber and fuel magazine having a grate at its bottom and communicating with a heating chamber through which conduits pass for air to be heated.

Another object of the invention is to provide the combustion chamber or fire box with an improved arrangement of fuel supporting grates and front and rear grates which allow air to pass horizontally through the fire box when a draft door at the front of the stove is opened and carry hot gases and other products of combustion into the heating chamber back of the combustion chamber.

Another object of the invention is to provide the heating chamber with air tubes extending vertically through the stove and increasing in diameter toward their upper ends so that as the air moves upwardly through the tubes and is heated, it may expand and flow very freely through the tubes.

Another object of the invention is to provide the stove with means for delivering warm air into the heating chamber near the back of the fire box where it will mix with unburnt gases delivered from the fire box and supply oxygen for mixing with these gases and causing them to ignite and thus supply additional heat for the air tubes instead of passing out of the heating chamber as unburnt gases.

Another object of the invention is to provide an improved arrangement of baffle plates in the heating chamber which cause the hot air and gases passing through this chamber to follow a tortuous path about the air tubes before reaching the outlet at the upper end of the back of the stove.

Another object of the invention is to provide the stove with an outlet for heated air at its top which is guarded by a readily removable grill and also provide under this grill a receptacle for holding a supply of water for imparting desired moisture to the hot air flowing upwardly from the stove.

Another object of the invention is to provide a stove simple in construction and very efficient in operation.

In the accompanying drawings:

Fig. 1 is a perspective view of the improved stove.

Fig. 2 is a sectional view taken vertically through the stove on the line 2—2 of Fig. 1.

2

Fig. 3 is a sectional view taken horizontally through the improved stove on the line 3—3 of Fig. 2.

Fig. 4 is a fragmentary sectional perspective view showing the front air inlet for the fire box and the draft door for controlling flow of air horizontally through the fire box.

Fig. 5 is an enlarged fragmentary sectional perspective view of the device for delivering oxygen to unburnt gases passing from the back of the fire box into the heating chamber.

Fig. 6 is a fragmentary sectional view showing the manner in which the gate or strip for controlling flow of air through the oxygen inlet is adjustably mounted.

This improved stove has a body formed of upper and lower sections 1 and 2, the lower section being supported upon a base 3 having depending supporting legs 4 and the upper section resting on and fitting snugly about the top of the lower section. The top 5 of the upper section is depressed and formed with a depending trough or receptacle 6 for holding water to supply moisture to hot air flowing upwardly from the stove.

Over the depressed top of the upper section is disposed a grill 7 formed of two sections connected by hinges 8 so that by grasping the knob 9, the front section 7' of the grill may be swung upwardly and rearwardly out of the way and allow access to the water receptacle 6 for filling the same when necessary. This also permits a cover 10 at the top of a fuel magazine 11, to be slid rearwardly to open position for depositing fuel in the magazine.

The fuel magazine extends vertically for the major portion of the height of the stove and its lower portion constitutes a combustion chamber or fire box 12 where fuel at the bottom of the magazine is burned. The rear wall of the magazine has its lower portion formed with a draft opening 13 and the front wall of the lower section 2 of the stove is formed with an opening 14 so that air may flow rearwardly through the fire box when the draft door 15 is opened. By this arrangement, flow of air through the fire box will be horizontal from front to back, and the fuel, such as wood, corn cobs, coal, or other solid fuel will be burned at the bottom of the supply

50 in the magazine and the fuel in the magazine gradually sink as it is consumed. The draft door is mounted for opening and closing by hinges 16 at its bottom and, in order to secure the door closed, or partially open, there has been provided 55 a resilient latch 17 which projects outwardly

from the front of the stove over the opening 14, in position for engagement by a curved bill 18 carried by the door. Gratings 19 and 20 having vertical slots, rest upon ledges 21 and 22 formed across the lower end of the rear wall of the magazine and across the front wall of the lower section below the draft opening 14 to hold the burning fuel or loose fuel in the fire box and these grating bars have handles 23 and 24 which project upwardly in the magazine and terminate near the upper end thereof so that when the cover 10 is shifted to open position, the handles may be grasped and the gratings drawn upwardly out of the fire box and magazine. Lugs 21 and 22 hold the gratings on the ledges.

The fuel rests upon grate bars 25 which extend across the bottom of the fire box and, at their ends, are formed with trunnions 26 resting in sockets formed in ledges 27 to rockably mount the grate bars and, at one side of the fire box, the grate bars are provided with depending arms 28 pivoted to a shaker bar 29. This shaker bar has its front end connected with a handle 30 which projects through the front wall of the stove at one side of the door 31 for the ash pit 32; this door being pivoted at its bottom by hinges 33 and releasably held closed by a bill or keeper 34 which is curved and engages a resilient latch 35. When the door 31 is opened, air may pass upwardly between the grate bars and out through the rear grating 19 as well as entering the fire box through the front grating and out through the rear grating. A very good control of draft is thus permitted and fuel at the bottom of the magazine caused to burn in the fire box without burning of fuel taking place in the magazine above the fire box.

The hot gases and smoke, as well as other products of combustion which pass through the rear grating 19 and the opening 13 in the rear wall of the fire box, enter the heating chamber 36 which extends the full height of the stove between the magazine and the rear wall of the stove and heat tubes 37 which extend vertically in the heating chamber with their lower ends mounted in collars 38 surrounding openings in the bottom of the stove and their upper ends mounted through collars 39 surrounding openings in the top 5 of the stove. These air tubes gradually increase in diameter toward their upper ends so that the air, which is heated and expands as it moves upwardly through the tubes, may flow freely. This also increases the area of the tubes and causes a more efficient heating of the air. Arcuate baffles 40, formed of metal, are mounted in the heating chamber and extend in overlapping relation to each other, as shown in Fig. 2, so that as the hot smoke and gases flow upwardly from the fire box to the outlet 41, to which a smoke pipe is to be attached, a tortuous path will be followed and heating of the tubes increased.

It is desired to have the unburnt gases which enter the heating chamber ignited and heat in the chamber 36 increased. To accomplish this, an opening or slot 42 is formed across the bottom of the stove. Plates or walls 43, forming a throat for the air inlet, extend upwardly from the bottom of the stove along front and rear edges of the opening 42 and, at their upper ends, carry a nozzle 44 which is formed of metal and has its upper portion arcuate in cross section and its front and rear walls formed with flanges 45 and 46 defining internal ledges which rest upon upper edges of the plates 43. A deflecting plate or baffle 47 extends upwardly in the nozzle at a

rearward incline from the flanged lower portion of the front wall of the nozzle, so that as air flows upwardly in the nozzle, it will be deflected rearwardly and then strike the arcuate upper portion of the nozzle which directs it forwardly and downwardly and out through the perforations 48 in the front wall without interference by the incoming air. This also causes the incoming air to make contact with the walls and upper portion of the nozzle as it flows through the nozzle, and the air will be heated before passing out through the perforations and jets of warm air will be discharged from the nozzle toward the opening 13. This air mixes with the unignited gases flowing into the heating chamber from the fire box and supplies oxygen to cause the gases to be ignited and burnt in the heating chamber. It will thus be seen that air tubes will be highly heated and air flowing through them well heated before flowing from the upper ends of the tubes and through the grating 7 to heat a room or building in which the stove is located. It is desirable to control the amount of air which flows through the air inlet 48 and, in order to do so, there has been provided a metal strip 49 serving as a damper for the air inlet. This strip or damper extends transversely of the stove against the under face of the stove bottom and its end portions slidably rest upon depressed portions 50 of the frame 3. Pins 51, carried by the bottom of the stove, engage through slots 52 formed in the strip diagonally thereof, and then when handle 53 of the strip is grasped and the strip shifted longitudinally, the strip will be shifted transversely into or out of covering relation to the air inlet, according to the direction in which the strip is shifted longitudinally. Eight openings 54 are formed through side walls of the stove above opposite ends of the nozzle 44, so that by looking through these openings, which are closed by glass, or other suitable transparent material, a person can determine whether the proper quantity of oxygen is being fed to the gases entering the heating chamber from the fire box.

Having thus described the invention, what is claimed is:

A stove comprising a body, a vertical partition extending between side walls of the body and dividing said body into a front fuel chamber and a rear heating chamber, said partition having its upper end connected with the top of the body and its lower end spaced from the bottom of the body, grate bars across the bottom of the fuel chamber, the lower portion of the fuel chamber constituting a fire box having the grate bars at its bottom and the portion of the body under the grate bars constituting an ash pit, air tubes extending vertically in the heating chamber, said tubes being tapered downwardly and having upper and lower ends mounted through openings in the top and the bottom of the body, and plates extending in opposite directions from the partition and the rear wall of the body for the full width of the body, said plates being spaced vertically from each other and disposed in overlapping relation to each other and each secured along one edge and having its opposite edge free, the plates being formed with openings through which the tubes pass and being arcuate transversely from their attached edges to their free edges and constituting upwardly bowed baffle plates for directing hot products of combustion upwardly in a zigzag course through the heating chamber back and forth between the rear wall

and the partition and serving as braces for the tubes.

THOMAS YOUNG.
